UNITED STATES PATENT OFFICE.

JULIUS H. SCHLAFLY, OF CANTON, OHIO, ASSIGNOR TO THE CANTON CULVERT AND SILO COMPANY, OF CANTON, OHIO, A CORPORATION OF OHIO.

CULVERT.

Application filed November 17, 1919. Serial No. 338,491.

To all whom it may concern:

Be it known that I, JULIUS H. SCHLAFLY, a citizen of the United States, residing at Canton, in the county of Stark and State 5 of Ohio, have invented a new and useful Culvert, of which the following is a specification.

The invention relates to improvements in sheet metal culverts of the sectional type 10 and has more especial reference to features of construction designed to guard said sections in shipping, erection and use.

The objects of the invention are to provide a culvert the end of which is provided 15 with an integral, annular bead which produce superior strength in the culvert and reinforces the end of the culvert in use where it projects through a bank or the like and is not protected by masonry or other 20 outside protecting means, and to generally improve and simplify corrugated culvert construction.

These objects are attained by first corrugating the sheet from which the culvert is 25 to be formed, then folding the end of the sheet back upon itself and then rolling the folded portion upon a rod or bar to form a reinforcing tubular bead of double thickness upon the end of the culvert and integral 30 therewith, the rod or bar upon which the bead is formed being either removed or left in the bead as desired.

The sheet is then formed into tubular shape 35 in the usual manner, the overlapping edges thereof being connected together in any well known manner to form the finished culvert.

The invention thus set forth in general terms is illustrated in the accompanying drawings forming part hereof, in which—

40 Figure 1 is a longitudinal sectional view through a portion of a corrugated culvert embodying the invention.

Fig. 2 is a side elevation of a portion of corrugated culvert.

45 Fig. 3 is an enlarged sectional view through the reinforcing bead, and

Fig. 4 is a view similar to Fig. 3, showing the rod within the bead.

A practical embodiment of the invention 50 is disclosed in the accompanying drawings, forming a part of this specification in which similar numerals of reference indicate corresponding parts throughout the several views.

55 At 1 is indicated a portion of a culvert,

which may be plain or corrugated or partly plain and partly corrugated, as desired, but circumferentially corrugated culverts are commonly preferred and I have so illustrated them. The culvert may be formed of 60 a single corrugated sheet bent into cylindrical form, the edges being overlapped and connected in any suitable and well known manner or the culvert may be made of two sheets each bent into semi-cylindrical form, 65 the edges being connected together by any usual method.

The sheet from which the culvert is formed is first corrugated in the usual manner after which the end of the sheet is 70 folded back upon itself for the required distance, forming a reinforced end upon the sheet of a double thickness of the sheet metal. The folded end of the sheet is then bent into U-shape upon a suitable die after 75 which a rod or bar 2 is placed within the bent portion of the sheet and the end of the sheet is bent or rolled upon the rod forming a bead 3 of double thickness upon the end of the sheet. The rod 2 may be left within 80 the bead, to further reinforce the same, as shown in Fig. 4, or it may be removed as shown in Figs. 1 and 3 thereby leaving a hollow bead.

The contour of the corrugated culvert 85 illustrated presents a series of alternate valleys and ribs 4 and 5 respectively and it will be noted that the culvert terminates in a valley in which the bead 3 is formed, the bead being substituted upon the end of the 90 culvert for a rib and the roll of the bead being continued tangent to the connected wall of the culvert.

After the bead has been thus formed upon the end of the sheet, one end of the bead is 95 cut away for a distance corresponding to the overlapped portions of the edges of the sheet, as shown in dotted lines at 6 in Fig. 2, and the sheet is bent or formed into tubular shape, in the usual manner, the longitudinal edges of the sheet being overlapped 100 as shown in dotted lines at 7 in Fig. 2 the overlapped portions being connected together by rivets 8 or their equivalents.

For the purpose of strengthening the 105 bead at the point where the ends thereof are butted together a sheet metal clip 9 is located around the joint in the bead and connected to the culvert upon each side of the joint by means of rivets 10 or the like. 110

This clip may be substantially U-shaped in the initial form and is placed around the joint in the bead and riveted to the culvert after which it is bent inwardly against the bead as shown at 11 in Fig. 3.

In forming the bead upon the end of the culvert the folded back portion at the end of the culvert may be of sufficient length to allow the rolled back edge of the bead to 10 rest upon the folded portion, as shown at 12 in Fig. 4, or it may be only long enough to allow the rolled back edge of the bead to be bent down adjacent to the periphery of the culvert, as shown at 13 in Fig. 3.

15 The strengthening bead thus formed upon the end of the culvert produces superior strength in the culvert, reinforcing the end of the same and preventing bending or other damage to said end in handling and transportation and provides an integral reinforcement upon the culvert which protects the exposed end of the culvert which may protrude through a bank or wall or the like, preventing serious injury to the culvert end 20 without the necessity of building a masonry reinforcement around the protruding end of the culvert.

This reinforcement is especially useful in places where a culvert is located through a 30 filled road, the end of the culvert projecting beyond the bank. In the event that a vehicle should slip over the edge of the road and strike the end of the culvert the reinforcing bead thereon would prevent serious damage 35 to the culvert.

I claim:

1. A sheet metal culvert provided upon its end with an integral tubular bead formed by rolling plural plies of the metal at the end 40 of the culvert upon themselves.

2. A circumferentially corrugated sheet

metal culvert having an annular tubular bead at its end formed by rolling plural plies of the metal at the end of the culvert back upon themselves.

3. A circumferentially corrugated sheet metal culvert comprising alternate circumferential ribs and valleys, the end of the culvert terminating at a valley, and plural plies of the metal at the end of the culvert being rolled back upon themselves to form an annular tubular bead.

4. A sheet metal culvert provided at its end with an annular reinforcing tubular bead formed by folding the metal at the 55 end of the culvert back upon itself and then rolling the folded portion upon itself.

5. A circumferentially corrugated sheet metal culvert comprising alternate circumferential ribs and valleys, the end of the culvert terminating at a valley and an annular reinforcing tubular bead of a double thickness of sheet metal formed at the end 60 of the culvert tangent to the bottom of the terminal valley.

6. A circumferentially corrugated sheet metal culvert provided at its end with an annular reinforcing tubular bead formed by folding the metal at the end of the culvert back upon itself and then rolling the 70 folded portion upon itself.

7. A sheet metal culvert provided upon its end with an integral tubular bead formed by folding the metal at the end of the culvert back upon itself and then rolling the 75 folded portion upon a rod.

8. A sheet metal culvert provided at its end with an integral annular tubular bead formed of a double thickness of metal from which the culvert is formed and a rod located within said bead.

JULIUS H. SCHLAFLY.
